Primary Examiner — Ricky Pham(74) *Attorney, Agent, or Firm* — ScienBiziP, P.C.(57) **CLAIM**

The ornamental design for a portable blender, as shown and described.

DESCRIPTION

FIG. 1 is a first perspective view of a portable blender, showing my design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded view thereof; and,

FIG. 10 is a perspective view thereof in a use state.

The broken lines are for environmental structures, boundaries, or illustrative purposes only and form no part of the claimed designs to be patented.
